SLUG CASTING MOLD

William L. Petersen, Springfield, N. Y., assignor
to Mergenthaler Linotype Company, a corpora-
tion of New York

Application July 11, 1932, Serial No. 621,800

8 Claims. (Cl. 199—54)

This invention relates to slug casting machines, such as linotype machines of the general organization represented in U. S. Letters Patent No. 436,532 to O. Mergenthaler, wherein molten metal is pumped into a slotted mold against a composed line of matrices to produce a printing slug or linotype, which is subsequently removed from the mold by an ejector advancing from the rear and driving the slug before it between a pair of trimming knives and into a receiving galley at the front of the machine.

In these machines, the mold usually comprises four distinct parts, namely, a body portion, a cap portion, and right-hand and left-hand liners, these parts defining the side and end walls of the mold slot or cavity. The liners are produced in various lengths and thicknesses and are selectively employed to vary the dimensions of the mold slot according to the size of the slug to be cast.

For slugs of the larger sizes, such as those of the head-letter or display variety, the cap portion of the mold is ordinarily formed with a series of core sections separated by fore-and-aft grooves and terminating short of the front face of the mold. A slug cast in a mold of this kind, therefore, is of skeleton or "recessed" form, comprising a relatively thin body portion, an overhanging character bearing portion and a series of supporting ribs for the overhanging portion. When such a skeleton slug is ejected from the mold, it is guided in its movement, at one side by the engagement of the upper (casting) surface of the mold body portion with the contiguous face of the slug body portion, and at the opposite side by the engagement of the lower surfaces of the core sections with the contiguous face of the slug body portion as well as by the engagement of the upper walls of the fore-and-aft grooves which separate the core sections (or, what amounts to the same thing, the lower surface of the cap portion proper) with the outer edges of the slug supporting ribs. However, when the rear edge of the slug approaches the front face of the mold, the upper side of the slug body portion moves out of engagement with the lower guiding surfaces of the core sections (due of course to the fact that the core sections terminate short of the front face of the mold), and the only upper guiding surface remaining thereafter is that of the cap portion or the groove walls against which the upper edges of the supporting ribs bear.

In practice, the slug supporting ribs frequently become crushed or damaged in the process of ejecting and trimming the slug, thus rendering

the slug unfit for use, and moreover such failure of the ribs often leads to more serious difficulties, such as the breakage or damaging of the ejector blade or the trimming knives. These objections and disadvantages, it has been found, are due to the tendency of the slug to twist or turn as it is pushed from the mold by the ejector blade (which, as well known, engages only the thin off-center body portion of the slug) and especially when the slug is guided near the end of the ejecting stroke by the supporting ribs alone at its upper side. While the supporting ribs are quite substantial and, in the case of long slugs, rather numerous, nevertheless they are not always capable of resisting or overcoming the canting or twisting of the slug, being crushed or broken down by the overpowering pressure which produces the canting or twisting action.

The present invention is intended to obviate the foregoing objections and disadvantages and contemplates a mold construction which, while adapted to cast a skeleton slug of the same kind as heretofore, will enable the slug to be properly guided until completely ejected from the mold. To this end, specifically, three of the core sections, one located centrally of the mold, and one located adjacent each end, are provided with guiding shoes which extend forwardly to the front face of the mold, and whose guiding surfaces are flush with the lower or slug guiding surfaces of the respective core sections. By reason of these additional guiding surfaces, the body portion of the slug is confined between coterminous upper and lower guiding surfaces which keep the slug under control until it is completely ejected from the mold, thereby preventing the canting or tilting of the slug notwithstanding the unevenly distributed pressure of the ejector blade.

In the accompanying drawings, the invention has been shown merely by way of example and in preferred form, and obviously many variations and modifications may be made therein which will still be comprised within its spirit. It is to be understood, therefore, that the invention is not limited to any specific form or embodiment, except insofar as such limitations are specified in the appended claims.

Referring to the drawings:

Fig. 1 is a horizontal transverse section through an old form of mold and its associated trimming knives, the mold being shown in its vertical or slug ejecting position;

Fig. 2 is an enlarged view similar to Fig. 1, but showing the improved mold with its slug guiding shoes formed on the core sections;

Fig. 3 is a perspective view of the mold cap for the improved mold;

Fig. 4 is a horizontal transverse section through another old form of mold and knife block, the mold again being shown in its vertical or slug ejecting position;

Fig. 5 is a view similar to Fig. 4, but showing the improved mold with its slug guiding shoes formed on the core sections; and

Fig. 6 is a view similar to Fig. 5, showing another form of improved mold with slug guiding shoes formed on the core sections.

As usual, the mold (carried by a rotatable mold disc O), comprises a body portion A and a cap portion B which define the opposite side walls of the mold slot or cavity, being separated by two intermediate liners, not shown, which define the opposite end walls of the cavity. The mold shown being of the head-letter or display variety, its cap portion B is provided with a series of core members or sections B' separated by fore-and-aft grooves B², the core members extending into the mold cavity and terminating short of the front face of the mold so as to form there a longitudinal recess B³.

The skeleton form of slug cast in the above mold presents a relatively thin body portion S¹ formed between the upper surface A¹ of the body portion A and the lower surfaces b¹ of the core members B', an overhanging face or character bearing portion S² (cast in the front recess B³), and a series of transverse ribs S³ projecting from the body portion and giving support to the face portion (these ribs being cast in the fore-and-aft grooves B² of the cap portion).

After the slug is cast and the mold carried by the rotatable disc O from its horizontal casting position to its vertical ejecting position (in which latter position it is shown), the ejector blade P is advanced against the rear edge of the body portion S¹ of the slug and, by continued forward movement, forcefully ejects the slug from the mold and between the slug trimming knives Q and Q¹, all in the usual manner.

Because of the recessed form of the cast slug, the left-hand knife Q will offer more resistance to the slug than the right-hand knife Q¹, and moreover the pressure exerted by the ejector blade P will be confined to the rear edge of the slug body portion S¹; for these reasons, the slug will tend to twist or cant toward the cap portion B of the mold as it is ejected and trimmed. During the first part of its movement, this tendency of the slug is overcome by the guiding surface A¹ of the mold body portion A and the guiding surfaces b¹ of the core sections B', these opposed surfaces bearing, as before stated, on the opposite sides of the slug body portions S¹. As the rear edge of the slug approaches the front face of the mold, its body portion S¹ moves out of engagement with the guiding surfaces b¹ of the core sections, leaving the slug to be guided at its upper side by the engagement of the supporting ribs S³ with the lower surface of the cap portion or the upper walls of the fore-and-aft grooves B². These supporting ribs S³, however, are not substantial enough to prevent the slug from twisting or canting in the mold, and they therefore become crushed or broken down (see Fig. 1, which shows the old form of mold).

This breaking down or crushing of the supporting ribs S³ is, of itself, sufficient to render the slug unfit for use, but the twisting of the slug produces other harmful results. Thus, it will be observed by reference to Fig. 1 that, as the slug

twists in the mold, its body portion S¹ is turned sidewise against the sharp edge of the left-hand trimming knife Q and the continued advance of the ejector blade causes either the rear edge of the body portion to be severed or else jams the slug between the two knives. In the latter event, the knives or the ejector blade, or both, may become damaged, requiring replacement.

According to the present invention, specifically (see Fig. 2), the lower slug guiding surfaces b¹ of certain of the core sections B' are extended forwardly to the front face of the mold, so as to be of the same fore-and-aft extent as the slug guiding surface A¹ of the body portion A. In the preferred embodiment illustrated, this is accomplished by providing the selected core sections at their lower front corners with guiding shoes C, whose lower surfaces are flush with the guiding surfaces b¹ of the respective core sections. In distributing the guiding shoes throughout the length of the mold, so that a minimum number thereof may be used to produce the desired result, one is located on a centrally located core section and one on a core section near each end of the mold (see Fig. 3). While it might be possible to obtain the desired result with a lesser or greater number of guiding shoes, it has been found that three, placed as shown, function in a thoroughly satisfactory manner.

The functioning of the guide shoes C will be apparent from Fig. 2. There it will be noted that, during ejection and trimming, the slug is guided in a straight path, with no danger of tilting or canting, because of the engagement of the mold surfaces with the body portion S¹ until the latter leaves the mold. These mold guiding surfaces are, of course, the top face A¹ of the mold body portion, on the one hand, and the lower faces b¹ of the core sections B' as well as the bottom faces of the guiding shoes C, on the other hand. The effect is as if the lower faces of the core sections themselves were extended to the front face of the mold. The supporting ribs S³ will also aid, as before, in the guiding of the slug at its upper side but now, with the shoes C present, they alone will not be required to effect such guiding just before the rear edge of the slug leaves the mold.

As shown in Fig. 2, the presence of the guiding shoes C cause recesses S⁴ to be formed in the slug at the junction of the body portion S¹ and the overhanging portion S². To avoid any weakening effect of these recesses, the guiding shoes C are bifurcated or slotted, as at C¹, whereby substantial supporting ribs will be formed on the slug in the regions of the recesses.

In Fig. 4, there is illustrated a form of mold D adapted to cast a skeleton or recessed slug with a character bearing surface or face portion T² overhanging the body portion T¹ at both sides. On the ribbed side of the slug, the overhanging portion is cast partly in the front mold groove B³ and partly within the routing notches of the matrices, while on the opposite side of the slug the overhanging portion is formed entirely within the routing notches of the matrices. During ejection, this slug will also have a tendency to cant or tilt, and this tendency is overcome, as in the first embodiment, by providing the core sections of the mold cap with the guiding shoes C, as shown in Fig. 5.

The form of mold illustrated in Fig. 6 differs from that first described only in that the lower portion of the front face of the cap portion B is formed with a longitudinal groove or recess B⁴

- opening into, but of less depth (fore-and-aft), than, the recess B³. In this recess B⁴, there is cast a part S⁵ of the character bearing portions S² which extends beyond the supporting ribs S³ 5 thereof. In ejecting a slug from a mold of this character, the difficulties before mentioned are greatly exaggerated. Thus, in the present instance, after the slug has been advanced far enough to bring the rear ends of the supporting 10 ribs S³ past the rear wall of the recess B⁴, it is obvious that the slug will be entirely devoid of any guiding influence, even the ribs being rendered impotent by the presence of the recess. By providing the core sections with the shoes C, 15 however, the slug can and will be guided properly until it is completely ejected from the mold since the shoes serve in conjunction with the mold body portion to furnish a bearing for the body portion of the slug throughout the whole 20 fore-and-aft extent of the mold.
- Although the guiding shoes have been described as integral parts of certain of the core sections, they could be detachably secured to the core sections, if desired.
- 25 The words "front", "rear", etc. are used herein in a relative sense only for purposes of description, and no limitation is intended.
- Having thus described my invention, what I claim is:
- 30 1. In or for a slug casting machine, a mold comprising side and end walls defining between them a mold cavity, and a core member supported within said cavity and terminating short of the front face of the mold so as to leave a recess in such 35 front face, said core member having its slug guiding surface extended across said recess substantially to the front face of the mold.
2. In or for a slug casting machine, a mold comprising side and end walls defining between them a mold cavity, and a series of core members supported within said cavity and terminating short of the front face of the mold so as to leave a recess in such front face, certain of said core members having their slug guiding surfaces extended across 45 said recess substantially to the front face of the mold.
3. In or for a slug casting machine, a mold comprising side and end walls defining between them a mold cavity, and a series of core members supported within said cavity and terminating short of the front face of the mold so as to leave a recess in such front face, certain of said core members being provided with slug guiding shoes extending 50 forwardly across said recess substantially to the front face of the mold, the slug guiding surfaces of said shoes being flush with the slug guiding surfaces of said core members.
4. In or for a slug casting machine, a mold comprising side and end walls defining between them 55

a mold cavity, and a series of core members supported within said cavity and terminating short of the front face of the mold so as to leave a recess in such front face, certain of said core members being provided with slotted slug guiding shoes projecting forwardly across said recess substantially to the front face of the mold, the slug guiding surfaces of said shoes being flush with the slug guiding surfaces of said core members. 80

5. In or for a slug casting machine, a mold comprising side and end walls defining between them a mold cavity, and a series of core members supported within said cavity and terminating short of the front face of the mold so as to leave a recess in such front face, three of said core members being provided with guiding shoes extending forwardly across said recess substantially to the front face of the mold, one of said guiding shoes being located centrally of the mold, and the other two being located adjacent opposite ends thereof, the slug guiding surfaces of said shoes being flush with the slug guiding surfaces of said core members. 85

6. In or for a slug casting machine, a mold comprising cap and body portions, said cap portion being formed with a longitudinal recess in the lower portion of its front face, and a core member supported within the mold cavity and terminating short of the front face of the mold so as to coincide with the rear wall of the longitudinal recess, 100 said core member having its slug guiding surface extended across said longitudinal recess substantially to the front face of the mold. 90

7. In or for a slug casting machine, a mold comprising cap and body portions, said cap portion being formed with a longitudinal recess in the lower portion of its front face, and a series of core members supported within the mold cavity and terminating short of the front face of the mold and constituting the rear wall of the longitudinal 105 recess, certain of said core members having their slug guiding surfaces extended across said longitudinal recess substantially to the front face of the mold. 110

8. In or for a slug casting machine, a mold comprising cap and body portions, said cap portion being formed with a longitudinal recess in the lower portion of its front face, and a series of core members supported within the mold cavity and terminating short of the front face of the mold and constituting the rear wall of said recess, certain of said core members being provided with slug guiding shoes projecting forwardly across said longitudinal recess substantially to the front face of the mold, the slug guiding surfaces of said 120 shoes being flush with the slug guiding surfaces of said core members. 125
